DONALD D. WHITACRE, OF WAYNESBURG, OHIO

BUILDING CONSTRUCTION

Application filed June 22, 1929. Serial No. 372,844.

This invention relates to building construction, particularly composite brick and tile wall construction and more particularly to header backer tile blocks which are disposed 5 behind and bonded with face brick to give body and strength to a wall.

I am familiar with the Eisemann Reissue Patent No. 17,137 reissued November 20th, 1928 and my invention constitutes an improvement over the construction disclosed in 10 that patent.

It is among the objects of my invention to provide a back-up block of relatively great strength and light weight which can be easily 15 set in the wall and which will lend itself to rapid and economical construction. Another object is to provide a back-up block having that portion adjacent the bricks so shaped that the bricks may be easily handled as they 20 are placed in the wall adjacent the back-up blocks. A further object is to provide blocks, which when bonded with face brick, will create numerous dead air cells within the wall whereby great insulating value is given 25 to the wall. A wall constructed according to my invention is relatively impervious to the passage of moisture. Another object of my invention is to provide blocks whose dimensions correspond to brick lengths or multiples 30 thereof and which may be easily broken into units corresponding to brick lengths or halves of brick lengths.

A further object is to provide blocks which may all be extruded from one die so that all 35 of the blocks necessary to be supplied to any given construction may be of the same size and shape. By this provision contractors and builders need only have on hand one kind and shape of tile block, which in their 40 original shape or in their readily divisible fractions, constitute all of the tile blocks necessary to fill in the door and window jambs, make the corners and otherwise completely back-up the face brick wall. Another 45 object is to reduce the weight of the back-up blocks eliminating one of the longitudinally extending webs or shells while still retaining the strength of the block and providing a large and serviceable bonding area between the blocks and header brick.

A further object is to arrange laterally extending double webs spaced apart substantially the thickness of a mortar joint of which the pairs are so arranged that the blocks may be divided into halves or quarters by fracturing them between adjacent webs of a pair. A further object is to provide wedge receiving grooves on the inner faces of the blocks in which wooden wedges may be inserted for receiving nailing strips, as shown in the 55 Swanson Patent No. 1,486,935, which grooves are arranged with relation to the double webs of the blocks whereby fracture of the blocks is facilitated and whereby nailing strips or the like may be readily secured to the inner face of the wall. A still further object is to provide an end-set and stepped back-up tile having a longitudinal dimension in the wall equal to the length of two bricks plus a mortar joint, and having an overall height and 60 width equal to the length of a brick whereby each block and fraction thereof has the same lateral cross-section and universal adaptation and conformity to brick dimension.

Other objects will appear from the following description of a preferred form of my invention, reference being had to the accompanying drawings. The essential characteristics are summarized in the claims.

In the drawings, Fig. 1 is a vertical perspective view taken at the end of the wall; Fig. 2 is a vertical section taken in a plane parallel to the plane in Fig. 1; Fig. 3 is a horizontal section taken along the broken plane 3-3 of Fig. 1; Fig. 4 is a horizontal section taken along the broken plane 4-4 of Fig. 1; Fig. 5 is a vertical section taken along the plane 5-5 of Fig. 1; Fig. 6 is a perspective of one of the back-up blocks showing the outer exposed face of the block as laid in the wall and illustrating the arrangement of grooves for wooden wedges; and Fig. 7 is a cut-away perspective view of the wall from the brick side; and Figs. 8 and 9 illustrate modified forms of the block illustrated in the preceding figures.

Referring particularly to Fig. 1, I illustrate a wall built of header backer tile blocks 1 and face brick 2. The face brick are preferably arranged in 5 stretcher courses between 140

header courses in the usual manner. The header bricks extend into the tile part of the wall and are bonded between adjacent tile blocks. As illustrated and fully described in the Eisemann reissue patent, mentioned above, each tile block is stepped as at 3 and adjacent pairs of tile blocks bond between them the inner ends of the header bricks. Likewise adjacent rows of header brick bond 10 between them and pairs of header tile blocks.

The tile blocks 1 are designed to be end-set in the wall, that is, the voids of the blocks as laid in the wall extend vertically. Referring also to Figs. 4, 8 and 9, my back-up blocks 15 have a longitudinal dimension as laid in the wall equal to the length of two brick plus one mortar joint. The lateral dimension of the block as well as the overall height equals the length of a brick so that the overall thickness of the wall, including both brick and tile, is substantially 12 inches. The block 1 has an outer shell 4 placed on the inside face of the wall end shells 5 and 6 and laterally extending pairs of webs 7 spaced apart the thickness of 20 a mortar joint extending from the outer shell toward and to the brick as laid in the wall. An inner shell 8 is formed integrally with the double webs 5 and the end shells 5 and 6 and are spaced inwardly an inch or more from the 25 ends of the webs and spaced away from the stretcher brick in the wall.

Referring particularly to Figs. 2 and 4, it will be seen that the inner shell 8 is spaced away from the brick so that between the shell 35 8 and the stretcher brick are formed a series of major air pockets 10 and minor air pockets 11, which pockets are closed at the top and bottom by the header bricks. Thus between the stretcher brick and the wall 6 of vertically 40 adjacent tile blocks, are formed closed air pockets which lend insulating value to the wall.

Referring also to Fig. 7, it will be appreciated that when the stretched bricks are laid 45 the mason may grasp the bricks and his hands may extend into one or the other of the major air pockets 10 without scraping his knuckles and fingers against the tile blocks and he may thereby more easily handle the bricks and 50 set them on their mortar beds. I regard it as one of the outstanding advantages of my invention that the extension of the webs and shells beyond the inner wall both provide dead air cells back of the stretcher bricks 55 and also facilitate the laying of the bricks. In Fig. 9 major air cells 10A of greater dimension further facilitate the laying of brick.

As mentioned above, the blocks 1 have longitudinal dimension as laid in the wall equal 60 to the length of two brick plus a mortar joint and I space the laterally extending double webs in such position that the blocks may be split between adjacent webs to divide them into halves or quarters. Thus the half blocks 65 will be substantially 8 inches long and the

quarter blocks substantially 4 inches long. As illustrated in Fig. 3, the longitudinal dimension of the blocks as laid in the wall equal substantially the width of four header brick plus three mortar joints and as will appear 70 from Fig. 5, the quarter portion of a block is substantially equal to the width of a header brick.

Referring particularly to Fig. 5, it will be seen that as the blocks are laid in the wall, there will be a continuous vertical alignment of webs and shells between overlapping blocks by reason of the fact that the double webs are spaced apart the thickness of a mortar joint. Thus for the sake of illustration, 75 I have shown at the top course in Fig. 5, and at the left end of the course a half block 15 lying above a full block 16 and lying adjacent the full block 17. It will be seen that the adjacent end walls of the blocks 16 and 17 are 80 in substantial vertical alignment with the middle adjacent webs of full block 16. In the same figure in the lower courses I illustrate a quarter block 18 lying adjacent a half block 19 and lying above a half block 20. It will be noted that the vertical web and shell 85 alignment is maintained and that closures are readily formed while maintaining a running bond in the wall.

To facilitate the fracture of the blocks into halves or quarters and also to provide for nailing strips and the like, I provide undercut grooves 25 laterally adjacent pairs of webs 7. I prefer that wedges, as disclosed in the Swanson patent mentioned above, be used, and as described in that patent those wedges may comprise oppositely slidable wooden members 26 and 27 which may be locked in the grooves when moved relative to each other. The function and arrangement of the wedges is of course entirely apart from this invention, but the arrangement of the grooves with relation to the spaced webs is novel and has a great utility, particularly 100 in fracturing the blocks into halves or quarters. 105

As illustrated particularly in Fig. 6, it will be appreciated that the zones of fracture as at 30 and 31, are remote from the exterior portions of the block. Thus the zone of fracture 30 in the inner shell 8 is spaced inwardly from the ends of the webs 7 and when the block is broken the webs 7 reinforce the shell on opposite sides of the fracture and prevent chipping or crazing adjacent the fracture. 110 The fracture at the zone 31 occurs in the bottom of the groove 25 and adjacent the juncture between the webs 7 and the wall 4 so that the face of the block is protected from chipping or crazing. Those skilled in the 115 art will appreciate that after the block has been broken, the roughened surface along the plane of cleavage may be chipped off with a trowel back to the plane of the webs without 120 chipping the faces of the webs. 125

As the brick and tile are built into the wall, it will be appreciated by referring particularly to Fig. 7, that the stretcher brick, as mentioned above, may be readily laid adjacent and in contact with the exposed inner ends of the webs 7 and that particularly the juncture of the webs with the inner shell 8 provides a large and satisfactory mortar bed either between adjacent tile blocks or between tile blocks and header brick. It will be seen that my construction lends itself to economical use particularly in that the tile blocks may be readily handled and fractured by the masons and that both the brick and tile may be easily laid in the wall.

In Figs. 8 and 9 are illustrated modifications of the blocks. In Fig. 8 the block 1B has the same overall dimension and general characteristics, but the lateral webs lie in the mid-portion of the quarter portions. Kerfs 35 are preferably provided to facilitate fracture. The webs extend beyond the inner shell to form air pockets and facilitate laying the bricks as described above. Such block when laid in the wall in quarter or half running bond have their webs and shells in vertical load bearing alignment.

The block 1A of Fig. 9 is similar in all respects to the block 1 described above, except that two pair of double webs have been eliminated. The block has thus the advantage of lightness, and the pockets 10A facilitate the laying of brick as mentioned above. For a given thickness of webs and shells, this block is somewhat weaker than the block 1, and of course the block 1A cannot be fractured into quarters. I contemplate certain instances when this block may advantageously be used.

Modifications of my invention may occur to those skilled in the art without departing from the spirit or major precepts thereof, and while I have illustrated and described a preferred form, I do not care to be limited in the scope of my patent other than by the claims appended hereto.

I claim:

1. A back-up tile block for brick and tile walls having inner and outer shells and laterally extending webs joining said shells and having extensions projecting beyond the shell of the block to space it from the brick facing part of the wall.

2. A back-up tile block for brick and tile walls having inner and outer shells and laterally extending webs joining said shells and having at least one integral extension projecting normally beyond the inner shell of the block engageable with the brick facing part of the wall for spacing the said inner shell from said brick facing.

3. An end-set back-up tile block for brick and tile walls having inner and outer shells of different height and laterally extending webs with stepped end surfaces joining said shells and having extensions projecting be-

yond the inner and shorter shell of the block to space it from the brick facing part of the wall.

4. A back-up tile block having front and back shells as positioned in the wall and having a plurality of pairs of laterally extending webs spaced from each other the thickness of a mortar joint joining the front and back shells of the block and extending beyond the back shell of the block to form spaced projections engageable with the brick part of the wall.

5. A back-up tile block having a relatively high front shell and a relatively low back shell as positioned in the wall and having a plurality of pairs of laterally extending webs spaced from each other the thickness of a mortar joint and joining the front and back shells of the block and having stepped ends midway between shells and extending beyond the back shell of the block to form spaced projections engageable with the brick part of the wall.

6. A backing tile for composite brick and tile walls having front and back shells and end shells, said block also having laterally extending webs lying parallel to the end shells and formed integrally with the front and back shells, said webs and end shells projecting beyond the back shell and forming projections for spacing the back shell from the brick part of the wall.

7. A backing tile for composite brick and tile walls having a longitudinal dimension equal to the length of two brick plus a mortar joint and having a gross lateral dimension equal to one brick and having front and back shells spaced from each other substantially less than the length of a brick and having parts extending beyond the back shell and normal thereto to a point a brick length from the face of the front shell.

8. A backing tile for composite brick and tile walls having a longitudinal dimension equal to substantially an even multiple of the length of a brick and having a gross lateral and vertical dimension equal to an even multiple of the length of a brick and having front and back shells spaced from each other substantially less than the length of a brick and having parts extending beyond the back shell to a point a brick length from the face of the front shell.

9. A backing tile for composite brick and tile walls having gross longitudinal vertical and lateral dimensions equal to substantially even multiples of the length of a brick and having a stepped horizontal surface and having a front shell of full height and back shell of reduced height spaced from each other substantially less than the length of a brick and having parts extending beyond the back shell to a point a brick length from the face of the front shell for engagement with the brick part of the wall.

10. A stepped back-up tile for bonding with header bricks of a composite brick and tile wall which when placed in the wall is as long as two brick plus a mortar joint, has an overall width equal to the length of a brick and an overall height equal to the length of a brick, said block having end shells and at least a centrally disposed pair of laterally extending webs spaced from each other the thickness of a mortar joint and an inner shell joining said webs and end shells and spaced away from the inner ends thereof, whereby the block may be fractured between said webs to form two blocks, each having three overall dimensions equal to substantially the length of a brick. 70
11. A back-up tile block having an inner shell and an outer shell and having laterally extending webs joining said shells and projecting beyond the inner shell, the outer shell being grooved adjacent its juncture with said webs and opposite the space between said webs whereby the block may be fractured between said webs at the base of the groove in the outer shell and between the projecting parts of the webs in the inner shell. 80
12. An end-set back-up tile block having an inner shell and an outer shell and having centrally disposed laterally extending double webs joining said shells and spaced apart the thickness of a mortar joint and projecting beyond the inner shell, the outer shell being grooved adjacent its juncture with said webs and opposite the space between said webs whereby the block may be fractured between said webs at the base of the groove in the outer shell and between the projecting parts of the webs in the inner shell to form separate equal parts. 85
13. An end-set back-up tile block for composite brick and tile walls adapted to be bonded with the inner ends of header brick, said block having a plurality of pairs of laterally extending webs in which the webs of a pair are spaced apart the thickness of a mortar joint, the pairs being spaced from each other a distance which permits each pair to bond a separate header brick, said block having an inner shell joining said webs and within the inner ends thereof whereby the inner ends of the webs engage the stretcher brick and form dead air cells defined by the bricks, the inner ends of the webs, and the inner shell of the block. 90
14. A back-up tile block for brick and tile walls having an inner shell adapted to be placed near but spaced from the brick facing part of the wall and having an outer shell exposed on the back face of the wall and being higher than the inner shell by substantially one-half the thickness of the facing brick, said block having a laterally extending portion joining said inner and outer shells and formed integral therewith and forming on one surface of the block a stepped por- 95

tion between the inner and outer shells, at least one of said laterally extending portions of the block having an integral extension projecting beyond the inner face of the inner shell of the block and adapted to contact with the brick facing part of the wall and spacing the inner shell of the block therefrom. 70

In testimony whereof I hereunto affix my signature this 5th day of June, 1929.

DONALD D. WHITACRE. 75
